Primary Examiner — Jennifer L Rempfer*Assistant Examiner* — Emily A Caven(57) **CLAIM**

The ornamental design for a cat exercise wheel, as shown and described.

DESCRIPTION

FIG. 1 is a front, right side perspective view of a cat exercise wheel, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the cat exercise wheel that form no part of the claimed design.

The additional dot-dash broken lines are for the purpose of showing enlarged areas and form no part of the claimed design.

1 Claim, 10 Drawing Sheets(56)
